UNITED STATES PATENT OFFICE.

MICHAEL PUSARESKI, OF LYNN, MASSACHUSETTS.

HEEL-AFFIXING MACHINE.

1,323,648.

Specification of Letters Patent.

Patented Dec. 2, 1919.

Application filed August 1, 1918. Serial No. 247,783.

To all whom it may concern:

Be it known that I, MICHAEL PUSARESKI, a citizen of Russia, and resident of Lynn, county of Essex, Commonwealth of Massachusetts, have invented an Improvement in Heel-Affixing Machines, of which the following description, in connection with the accompanying drawings, is a specification, like characters on the drawings representing like parts in each of the several views.

This invention is directed to a machine for affixing heels to shoes and particularly to a mechanism for securing heels to shoes by means of screws or like attaching means, as commonly practised in securing high heels of wood or the like to ladies' shoes. A principal object of the invention is to provide means operative rapidly and effectively in a semi-automatic manner to position accurately and hold secure the shoe sole and upper with respect to the heel while the screws are forced into place, and in conjunction therewith to provide means operative rapidly and reliably to drive the several screws home simultaneously. The foregoing and other objects and advantages of the invention will more fully appear from the following detailed description, and the distinctive features of novelty will be pointed out in the appended claims.

Referring to the drawings:

Figure 1 is a front view of a machine constructed in accordance with my invention with parts broken away;

Fig. 2 is a plan view thereof with certain top connections broken away;

Fig. 3 is a plan view of the lower part of the machine and with intermediate connecting parts in section;

Fig. 4 is a side elevation with parts broken away and in section;

Fig. 5 is a partial vertical section on line 5—5 of Fig. 2;

Fig. 6 is a detail horizontal section on line 6—6 of Fig. 1;

Fig. 7 is a perspective view of a presser head and templet removed; and

Fig. 8 is a detail elevation of one of the screw driver members.

The operative parts of the machine are mounted on a suitable pedestal frame 10, the lower part of which is broken away, but may extend downward far enough so as to locate a platform top 10^a thereof at a convenient elevation above the floor for the operator. On this platform 10^a are fixed adjustably spaced

apart parallel guide ways 11, 11 formed with inturned flanges 11^a to hold for sliding movement two blocks 12, 13 which fit together and have formed in their meeting 60 sides co-operative portions of a heel seat 14. The guide ways 11 are shown as held to the platform 10^a by clamp bolts 15 which are passed through elongated slots 16 in lateral projections 17 at the ends of said guide 65 ways, this adjustment permitting said guide ways to be shifted laterally and adjusted accurately to position the heel socket blocks 12, 13 correctly, with respect to the operative devices to be described. A stop plate 70 18 with an upturned front edge 18^a is adjustably clamped to the base to limit the forward movement of the block 12 by means of a clamp bolt 19 which is passed through an elongated slot 20 of said plate into the 75 base. The blocks 12, 13 have passed horizontally therethrough tie rods 21, 21 at each side, these rods having headed ends and being of a length to permit a small amount of relative movement of the blocks 12, 13 toward and away from each other. The block 13 which has formed therein the rear part 80 of the heel seat, has fixed thereto a rearwardly projecting arm 22 equipped with a pin 23 engaging in a slot 24 of a lever arm 85 25 which is fixed to a shaft 26 horizontally journaled in the frame. This shaft has fixed at its outer end an operating handle lever 27 so that by shifting this lever the block 13 may be moved outwardly to first separate 90 it from the block 12 and open the socket 14 for the reception of the heel, and thereafter move with it the block 12 to some little extent until the lever 27 comes against a fixed stop 27^a suitably positioned on the machine 95 frame. At one side of the machine frame 10 is adjustably fixed an upright column 28, the lower portion of this column having dovetailed sliding engagement with the frame as indicated at 28^a and this column 100 may be adjustably clamped to the frame in position to locate the operating devices to be described correctly with reference to the heel seat just described, by means of clamping bolts 29 which extend through a vertically 105 elongated slot 30 of the frame and through said column. The column 28 has a lateral bearing extension 31 extending out over the platform 10^a at some distance thereabove with an upward extension 32 extending up 110 in parallelism with the upper end of the column 28 proper. The lateral extension 31

has slidably guided therein a vertical rod 33 the lower end of which has pin and slot connection 34 with a lever 35 fulcrumed to the frame at 36 and having link 37 pivoted to its outer end which may extend down to a treadle (not shown). The rod 33 has fitted thereon a compression coil spring 38 which presses upward against a collar 39 fixed on said rod, the lower end of said 10 spring reacting against the column extension 31, thus tending to keep the rod 33 and parts associated therewith elevated. The upper end of the rod 33 has fixed thereto a stout plate 40 which has fixed thereto spaced 15 apart depending presser bars 41, 41. These bars extend down to a point relatively near the platform 10^a where their lower extremities are inturned toward each other as seen at 41^a and have fixed at the ends thereof a 20 presser head and templet 42. The purpose of the inturned bar extremities 41 is to permit them to extend down inside of the heel end of the shoe and the presser head and templet 42 is of a size to fit approximately 25 within the heel cavity of the shoe. By the action of the spring 38 the presser head 42 is normally held elevated some little distance above its operative position to which it is adapted to be depressed by operation of 30 the treadle connection 37. The top portions of the column proper 28 and of the vertical extension 32 are equipped with vertical guide ways 43 in which is slidably fitted a frame 44 having horizontally journaled 35 therein a shaft 45. The shaft 45 has fixed thereon a spur pinion 46 which meshes with a rack 47 fixed to the extension 32 so that as said shaft 45 is turned the frame 44 will be raised or lowered according to the direction 40 of such turning movement. The shaft 45 is equipped with a hand wheel or handle 48 and it also has fixed at its inner end a bevel pinion 49 which meshes with a bevel gear 50 suitably journaled in the frame 44 45 having for this purpose at its top a short stud extension 51 which fits into a socket in a top portion of the frame and having at its bottom a shallow seat in which fits a circular boss 52 extending up from the frame. 50 The gear 50 is made hollow with an internal gear 53 formed therein which meshes with a series of pinions 54, shown as three in number and fixed at the tops of a series of screw driver shafts 55. The pinions 54 are relatively 55 thin or narrow faced as compared with the width of the face of the internal gear 53 so that said pinions will remain in mesh with said gear throughout a short range of sliding movement with respect thereto. The shafts 55 have fixed thereon bearing sleeves 56 which are slidably fitted through the extension 31 as seen at 57 and compression coil springs 58 are fitted on the shafts to press against the tops of these 60 bushing sleeves with the other ends thereof

re-acting against the sliding frame 44 whereby the shafts 55 are normally spring held at their downward limit of movement with respect to the frame 44 and with the pinions 54 resting against the surface of the 70 boss 52. The lower ends of the shafts 55 are equipped with screw driver heads 59 secured thereon in any suitable manner as by threaded nipples 59^a of the screw driver heads fitting into threaded sockets of said shafts. 75 The shafts 55 with the screw driver heads thereon are mounted in the slide frame 44 and guided in the fixed extension 31 in spaced apart relation as required to engage the three screws which are usually driven through the heel seat of the shoe into the heel to secure the parts together. The presser head 42 is formed with templet holes 60 spaced apart according to the required spacing of the screws, these holes being of a 80 size to permit the screws *s* to slip therethrough and the operative end of the screw drivers to enter therein.

In use the presser head 42 being normally held elevated by the spring 38, the shoe *S* 90 is applied thereto with the presser head fitting into the heel portion. Then the heel *H* is put into the then open socket 14, the blocks 12, 13, being then moved rearwardly and spaced apart. Thereupon the treadle is 95 operated and the presser head brings the heel seat of the shoe down against the heel *H*, which it will be understood is at this time mostly thereunder, though a little to the rear of its final position. Then the 100 handle 27 is operated to press the blocks 13, 12 forward and together, resulting in sliding and pressing the heel *H* forward closely against the small ledge or lip *L* which is provided therefor in usual practice, the shoe 105 being at this time securely held against displacement by the presser head 42. Then while the treadle is still held depressed to keep the heel seat of the shoe firmly clamped to the heel, the hand wheel 48 is operated moving the slide frame 44 downward by the rack and pinion connection 46, 47 and at the same time through the described connections rotating the screw driver shafts 55. As the rotating screw driver heads 59 110 engage the screws *s* which have been previously supplied to the templet holes 60 of the presser head, the screws will be driven into the heel, and in the event that either of the screw driver bits does not immediately find its way into the kerf of the screw, the shaft 55 bearing the same is permitted to yield backward against the spring 58 to the extent required until the bit is seated in the kerf. The backward yielding thus 115 permitted the shafts 55 and as allowed by the wide face of the gear 53, is also of importance in allowing for irregularities in the forward drive of the screws as compared with the downward positive feed of the 120

130

slide frame 44 and thereby it is insured that the screws will always be driven in with a proper forward rotary movement without mutilating the thread hold in the wood.

5 With the described mechanism the rapid and accurate positioning and assemblage of the shoes with the heel is attained and the securing elements may be applied simultaneously and much more rapidly than as at present practised. I am aware that the invention may be embodied in other specific forms without departing from the spirit or essential attributes thereof, and I therefore desire the present embodiment to be 10 considered in all respects as illustrative and not restrictive, reference being had to the appended claims rather than to the foregoing description to indicate the scope of the invention.

20 Having described my invention, what I claim as new and desire to secure by Letters Patent is:

1. Heel affixing apparatus, comprising a presser head mounted for up and down movement and adapted to fit into the heel of a shoe, means for positioning a heel under said presser head and somewhat to the rear of its normal position with respect to a shoe applied to said head, and means for clamping the heel and moving it forward to operative position directly underneath the heel seat of a shoe on said presser head.

2. Heel affixing apparatus, comprising a presser head mounted for up and down movement and adapted to fit into the heel of a shoe, means for positioning a heel under said presser head and somewhat to the rear of its normal position with respect to a shoe applied to said head, means for clamping the heel and moving it forward to operative position directly underneath the heel seat of a shoe on said presser head, and means for driving screws through the heel portion of the shoe into said heel while thus 45 assembled.

3. Heel affixing apparatus, comprising a presser head templet mounted for up and down movement, and adapted to fit within the heel of a shoe, a heel socket mounted for 50 movement laterally of said presser head and underneath the same and constructed also for opening and closing movement by said lateral movement, and screw driving means operatively combined with said templet presser head to drive screws therethrough

for securing the heel portion of the shoe to the heel, said presser head templet constructed, and coöperatively arranged to locate the shoe with respect to the heel in the heel securing operation and also to hold the 60 screw driver means in correctly alined relation.

4. Heel affixing apparatus, comprising a templet presser head mounted for vertical movement and adapted to fit within the heel portion of a shoe, heel holding means mounted for movement to locate a heel in operative position with respect to a shoe fitted on said presser head, and means operatively combined with said templet presser head for simultaneously driving home a plurality of screws therethrough to secure the heel to the shoe, said presser head templet constructed, and coöperatively arranged to locate the shoe with respect to the heel in the heel securing operation and also to hold the screw driver means in correctly alined relation.

5. Apparatus of the kind described, comprising a presser head adapted to fit within the heel portion of a shoe, a heel carrier mounted for movement underneath said presser head to bring a heel carried thereby into operative position with respect to the shoe, said heel carrier equipped with a heel socket with provision for opening and closing the same to receive a heel and then clamp the same as it is moved under the presser head, and means operative through said presser head for simultaneously driving home a plurality of screws to secure the heel to the shoe.

6. Heel affixing apparatus, comprising a templet presser head, treadle controlled means for moving the same vertically, a heel carrier formed of two relatively movable parts with a heel receiving socket opening to receive the heel and closing as said carrier moves to operative position, and a multiple screw driver mechanism operative through said templet presser head as it clamps the shoe on to the heel for driving screws therethrough into the heel.

In testimony whereof, I have signed my 105 name to this specification.

^{his}
MICHAEL X PUSARESKI.
